UNITED STATES PATENT OFFICE.

HARRY BASTOW, OF CRAFTON, PENNSYLVANIA.

MANUFACTURE OF VACUUM VESSELS

1,256,427.

Specification of Letters Patent. Patented Feb. 12, 1918.

Application filed March 14, 1917. Serial No. 154,721.

To all whom it may concern:

Be it known that I, HARRY BASTOW, a citizen of the United States, and a resident of Crafton, in the county of Allegheny and State of Pennsylvania, have invented new and useful Improvements in the Manufacture of Vacuum Vessels, of which the following is a full, clear, and exact description.

The invention relates to vacuum bottles and similar vessels made of glass and having hollow walls.

The object of the invention is to provide certain new and useful improvements in the manufacture of vacuum vessels whereby such vessels of various shapes and to be used for a variety of purposes can be readily and economically produced, such, for instance, as ordinary vacuum bottles, or more squat-wide-mouthed vessels for containing food after baking it and sufficiently attractive for table use, or vessels for fireless cookers or the like.

The desired result is accomplished by a method which consists essentially in molding a blank having a bottom, a double wall rising integrally from the bottom, and a single wall depending integrally from the said bottom, sealing the ends of the double wall together to form a chamber between the members of the double wall and "cutting shut" the said depending wall to form a chamber between it and the said bottom.

In order to carry this method into effect use is made of a mold, such, for instance, as shown in the accompanying drawings forming a part of this specification, in which similar characters of reference indicate corresponding parts in all the views.

Figure 1 is a sectional side elevation of the mold and the blank formed therein;

Fig. 2 is a sectional plan view of the same on the line 2-2 of Fig. 1;

Fig. 3 is a sectional side elevation of the vacuum vessel; and

Fig. 4 is a sectional side elevation of a modified form of the mold.

The base 10 of the mold is provided on top with an undercut shoulder 11 from which rises a core 12, and on the said base 10 are adapted to be set the two or more side parts 13, 14 of the mold, the parts being detachably connected with each other

by the usual eyes 15, 16 and pins 17. The mold sides 13 and 14 when closed fit with their lower portions snugly against the shoulder 11 of the base 10, as plainly shown in Fig. 1. On the top of the mold sides 13 and 14 is placed a ring 20 provided on its under side with a short shoulder 21 fitting against the inner face of the mold sides 13 and 14. From the ring 20 depends an annular core 22 spaced from the inner surface of the mold parts 13, 14 corresponding to the thickness of the outer wall of the vessel to be made, as hereinafter more fully explained. The bottom of the core 22 is spaced from the top of the core 12, and from the said bottom of the core 22 depend one or more pins 23 adapted to rest on top of the central core 12. The opening 24 of the ring 20 is arranged for the passage of the plunger 25, which latter is spaced from the inner surface of the core 22 and the top of the core 12, the side of the latter being spaced from the corresponding opposite inner surface of the mold sides 13 and 14, as plainly shown in Fig. 1.

When the mold sides 13 and 14 are in closed position on the base 10 and the ring 20 is in position on top of the mold sides 13 and 14 then hot glass in proper quantity is placed into the mold and then the plunger 25 is forced downward in the usual manner for pressing the glass in the mold with a view to provide a bottom 30, outer and inner walls 31, 32 rising in spaced relation from the said bottom, and a wall 33 depending from the bottom 30. The vessel blank thus made is removed from the mold after the plunger 25 is withdrawn, the ring 20 lifted off, and the sides 13, 14 unlocked and removed to permit of lifting the vessel blank off the central core 12. The molded vessel blank is now placed in a snap or holding tool and "warmed in" and reheated at its upper edges for sealing purposes. The outer ends of the walls 31 and 32 are next sealed together to form a vacuum joint 34 and a chamber 35 between the said outer and inner walls 31 and 32. This sealing operation is preferably done by spreading the upper portion of the inner wall 32 by the use of a buffer while spinning the blank around by the use of the snap or holding

tool until the ends of the walls 31 and 32 merge one into the other. Instead of bending the upper end of the inner wall 32 outward as described, the upper end of the outer wall 31 may be bent inward to merge with the inner wall 32, or the upper ends of both walls 31 and 32 may be bent toward each other to finally merge and form a vacuum joint. After sealing the inner and outer 10 walls 31 and 32 the molded vessel blank is next reversed in the snap or holding tool and the wall 33 is "warmed in" and "cut shut," that is, a compass-shaped tool is applied to the outer diameter near the bottom 15 while the blank is being spun around in the snap and the circumference is gradually restricted until the opening is completely closed, that is, the material of the edge of the wall 33 is integrally united to form with 20 the bottom 30 another chamber 36, as plainly indicated in Fig. 3.

It will be noticed that by the method described two chambers are formed, one an annular chamber in the double wall and the 25 other between the two bottoms 30 and 33.

It will also be noticed that on lifting the ring 20 the projections or pins 23 leave openings 37 which connect the chambers 35 and 36 with each other. One of the mold parts, 30 as shown, the mold part 14, is provided on its inner face with a lug 38 adapted to form a hole 39 in the outer wall 31 for connection with a vacuum producing device to form a vacuum in the connected chambers 35 and 35 36 in the usual manner, it being understood that the hole 39 is sealed up after the desired vacuum is obtained.

It is understood that by the use of the holes 37 only one vacuum producing operation is needed as without such holes 37 it would require the opening 39 shown and another similar opening in the wall 33 to exhaust the air from the chamber 36. The hole 39 may also be used for introducing a 45 silvering solution into the chambers 35 and 36 and pouring out the remainder after the precipitation is completed.

In the modified form shown in Fig. 4, the core 22 on the ring 20 is dispensed with, 50 and the plunger 40 is provided on the under side with an annular groove 41 thus providing a core 42 which corresponds to the core 22 to produce the inner wall 32 of the vessel blank.

From the foregoing it will be seen that 55 by the method described, a large variety of vessels can be produced, such, for instance, as the ordinary vacuum bottles, vessels of the more squat open-mouthed shape used for 60 retaining food after baking until the food is to be served, or vessels that may be used in fireless cookers by means of which foods are given a preliminary heating on an ordinary stove and cooked by retaining their 65 heat by means of heat-insulating apparatus.

It is understood that covers having a vacuum chamber are made in the same manner as described.

It will also be noticed that by this method glass vessels can be very cheaply manufactured. 70

Having thus described my invention, I claim as new and desire to secure by Letters Patent:—

1. The method of manufacturing hollow 75 wall vessels which consists in molding a blank having a bottom, a double wall rising integrally from the bottom and a single wall depending integrally from the said bottom, sealing the ends of the double wall together 80 to form a closed chamber between members of the double wall, and cutting shut the said depending wall to form a closed chamber between it and the said bottom.

2. The method of manufacturing hollow 85 wall glass vessels, consisting in molding a blank having a bottom, a double wall rising from the bottom and a single wall depending from the bottom, uniting the upper spaced ends of the inner and outer walls 90 of the double wall to form a vacuum chamber, and bending the single depending wall inward to unite the material of the edge of this wall to form with the said bottom a second vacuum chamber. 95

3. The method of manufacturing hollow 100 wall glass vessels, consisting in molding a blank having a bottom, a double wall rising from the bottom with apertures in the bottom between the outer and inner walls of the 105 said double wall, and a single wall depending from the bottom, uniting the upper spaced ends of the inner and outer walls of the double wall to form a vacuum chamber, and bending the single depending wall inward to unite the material of the edge of this wall to form with the said bottom a second vacuum chamber communicating with the first named chamber. 110

4. The method of manufacturing hollow 115 wall glass vessels, consisting in molding a blank having a bottom, spaced inner and outer walls rising from the said bottom, and a single wall depending from the said bottom, bending the upper portion of the 120 inner wall outward and integrally uniting it with the outer wall to form a vacuum chamber between the walls, bending the single wall inward, and uniting the material of the edge of this wall to form with the bottom a second vacuum chamber.

5. The method of manufacturing hollow 125 wall glass vessels, consisting in molding a blank having a bottom from which rise integrally spaced inner and outer walls and 130 integrally uniting the upper portions of the said walls to form a vacuum chamber between them.

6. The method of manufacturing hollow 135 wall glass vessels, consisting in molding a

blank having a bottom from which rise integrally spaced inner and outer walls, bending the upper portion of the inner wall outwardly and integrally merging the edge of 5 the inner wall with the outer wall to form a vacuum chamber between the said inner and outer walls.

7. The method of manufacturing hollow

wall glass vessels, consisting in molding a blank having a bottom, and a wall depending integrally therefrom, bending the said wall inward and integrally uniting the material of the edge of the wall to form with the said bottom a vacuum chamber. 10

HARRY BASTOW.
